UNITED STATES PATENT OFFICE.

MARK A. DEFIBAUGH AND RALPH J. THIEMAN, OF BATTLE CREEK, MICHIGAN, ASSIGNORS TO H. B. SHERMAN MANUFACTURING CO., OF BATTLE CREEK, MICHIGAN, A CORPORATION OF MICHIGAN.

CENTRIFUGAL STARTING SWITCH.

Application filed November 28, 1921. Serial No. 518,248.

To all whom it may concern:

Be it known that we, MARK A. DEFIBAUGH and RALPH J. THIEMAN, citizens of the United States, residing at Battle Creek, in the county of Calhoun and State of Michigan, have invented certain new and useful Improvements in Centrifugal Starting Switches; and we hereby declare that the following is a full, clear, and exact description thereof, reference being had to the accompanying drawings, which form part of this specification.

This invention relates to automatic starting switches of the centrifugal type such as are used for opening the starting circuit of split-phase induction motors.

The object of the invention is to simplify the construction of such devices, to reduce the number of parts required to perform the necessary movements, and also to reduce the cost of manufacture.

The switch, in brief, comprises radial sliding weights adjustably spring connected, means connected therewith for actuating a yoke or arm attached to a bushing sliding freely in an axial direction on the shaft of the rotor, a contact carrier insulated from the bushing, an annular contact mounted thereon, and stationary insulated contacts cooperating with the annular sliding contact.

We will explain the invention more fully with reference to the accompanying drawings, which illustrate one practical embodiment of the invention, and an understanding thereof will enable others to adopt and use the invention. In the claims we have summarized the essentials of the invention, and the novel features of construction and a novel combination of parts for which protection is desired.

In said drawings:

Fig. 1 is a sectional view of the switch as applied to a starting motor, the switch being shown in closed position and parts of the motor being conventionally shown to indicate the usual location of the switch.

Fig. 2 is a view similar to Fig. 1 showing the switch open.

Fig. 3 is a sectional view on the line 3-3 Fig. 1 looking in the direction of the arrows, the rotor being removed.

Fig. 4 is a similar sectional view on the

line 4-4 Fig. 2 looking in the direction of the arrows. 55

Fig. 5 is a diagram illustrating the electrical connections.

The switch is of the type in which sliding weights are used to actuate a circuit closing device in the starting winding of the motor. The motor may be of any suitable make or type and in the drawings we have simply conventionally indicated a rotor A of a motor, having a shaft B journaled in bearings C of any suitable type, on one end 60 D of the motor casing.

To the rotor A, adjacent the bearing C is secured in any suitable manner a preferably circular plate 11, which is concentric with the shaft B. On this plate 11, at diametrically opposite sides of the shaft B are slidably mounted plates or "weights" 1, 1', which are movable, radially of the rotor, to or from the shaft B. The slideable plates or "weights" 1, 1' may be provided with 70 slots 1^c through which pass screws 2 by which the plates are slidably retained on studs 10 projecting from the face of plates 11 while permitting weights 1, 1' to slide 75 radially of the rotor as described. 80

The weight plates 1, 1' are connected by springs 9, 9' arranged at opposite sides of shaft B, said springs controlling the weights when the rotor is at rest and also exerting a controlling influence on the weights 1, 1', 85 during rotation of the rotor. The springs should be of uniform strength, and so proportioned that after the rotor is started and when it reaches a certain predetermined speed of rotation, the weight plates 1, 1' 90 will move outward radially, under the influence of centrifugal force overcoming the resistance of springs 9, 9', and will actuate the switch contacts, as hereinafter described.

Attached to the inner side of the casing 95 D concentric with the shaft B is an insulating plate 12 to which are attached two diametrically opposite stationary contact segments 7 and 7' which are preferably electrically connected in the starting winding 100 and feed circuit of the motor as indicated in Fig. 5 or in any other suitable manner.

Slidably mounted on the shaft B, between the plates 11 and 12, is a sleeve 5 on the end of which, adjacent plate 12, is mounted 105 an insulating ring 8. Upon this insulating

ring 8 opposite the segment 7 is mounted a contact ring 6, which serves to close the circuit between the stationary contacts 7, 7' when the motor is in starting position 5 (Fig. 1).

An actuating member or yoke 3 is fastened to the rear end of the sliding sleeve 5 and the diametrically opposite projecting arms 3^a, 3^b of yoke 3, extend through openings in oppositely projecting arms 1^a and 1^b of the sliding weights 1, 1' as shown in Figures 1 and 2.

The arms 3^a, 3^b are preferably inclined at an angle of approximately 45° to the shaft 15 B so that said arms lie at an angle of about 45° to the weight plates 1, 1' and slide freely through openings in the arms 1^a, 1^b as shown in Figs. 1 to 4. The arms 1^a, 1^b of the weight plates 1, 1' are also preferably inclined at about an angle of 45° to the plates 20 and shaft, so that the engaging arms 1^a, 3^a; and 1^b, 3^b stand at an angle of about 90°, or at right angles, to each other. As the weight plates 1, 1', move outward, under the action 25 of centrifugal force, the engaging arms 1^a, 3^a; and 1^b, 3^b will move sliding sleeve 5 proportionally, and draw the contact ring 6 away from the stationary contact segments 7, 7', and open the circuit through the starting winding.

When the main circuit is opened, and the rotor comes to a stop, the sliding weight plates 1, 1' will be drawn inwards toward the shaft by the springs 9, 9', and as they 35 move inward the interengaging arms, 1^a, 3^a; 1^b, 3^b, will move the sleeve 5 proportionally outward until the contact ring again makes electrical connection with the stationary segments 7, 7', and thus automatically puts the 40 circuit in proper condition for again starting the rotor.

As the controlling springs, 9, 9' are liable to vary somewhat in strength from each other, we preferably provide means for 45 varying or adjusting the tension of these springs. In the construction shown in the drawings (Figs. 3 and 4) each sliding weight plate 1 and 1' is provided with a plurality of holes 14 with any of which the related ends of springs 9 and 9' may be engaged. These holes vary in distance from the center of the shaft and the tension of either spring can be changed by hooking in one or the other of the holes. The 50 invention is not restricted to the use of two holes for each end of the springs 9, 9' as it is evident that more holes may be provided if desired. These holes provide a simple and effective means for adjusting the tension of the springs; and also a simple means for varying the speed at which the sliding weights will, through the action of centrifugal force, overcome the resistance of the 55 springs.

To enable the contact ring 6 to freely ad-

just itself to contacts 7, 7' the ring 8 may be loosely mounted on sleeve 5 and a helical expansion spring 4 strung on the sleeve between the ring 8 and the ring 3 to yieldingly hold the ring 8 against the flange 5^a on the 70 outer end of the sleeve; so that when the parts are in normal position as shown in Fig. 1, contact of the parts 6 and 7 will be insured, so that when the line current is applied to start the motor, the starting 75 winding will be energized efficiently.

What we claim is:

1. In a centrifugal starting switch, an insulated contact carrier, a rotatable member, radially movable weights on said member, 80 and oppositely inclined intersecting arms on the carrier and weights whereby said carrier is moved in an axial direction by and in proportion to the radial movement of the weights.

2. A centrifugal starting switch having in combination radial sliding weights spring connected, an insulated contact carrier movable at right angles to the sliding weights and an angular arm or yoke attached to the contact carrier passing freely through the sliding weights so as to actuate the contact carrier when the weights move radially.

3. A centrifugal starting switch having 95 in combination radial sliding weights adjustably spring connected, an insulated contact carrier movable at right angles to the sliding weights, and means integral with the weights for actuating the insulated contact carrier in an axial direction by and in proportion to the radial movement of the weights.

4. A centrifugal starting switch having in combination radial sliding weights adjustably spring connected, a bushing sliding freely in an axial direction on the shaft of the motor and having an angular yoke or arm, means integral with the weights for actuating the bushing, a contact carrier insulated from the bushing, an annular contact mounted thereon, and stationary insulated contacts cooperating with the annular sliding contact as described.

5. In a centrifugal starting switch of the character specified, a radially movable weight member having an arm projecting therefrom at an angle, and an axially movable member having an arm projecting therefrom at an angle, said arms being engaged whereby the radial movement of the weight member causes a longitudinal movement of the axially movable member, a contact ring carried by said member, and fixed contact segments adapted to be engaged by said ring when the parts are in starting position.

6. In a centrifugal starting switch of the character specified, a radially movable weight member having an arm projecting therefrom at an angle of about 45°, an ax-

ially movable sleeve having an arm projecting therefrom at an angle of about 45° , said arms being slidably engaged whereby the radial movement of the weighted member 5 causes a longitudinal movement of the sleeve, substantially as described.

7. In a centrifugal starting switch of the character specified, a radially movable weight member having an arm projecting 10 therefrom at an angle of about 45° , an axially movable sleeve having an arm projecting therefrom at an angle of about 45° , said arms being adapted to be engaged whereby the radial movement of the 15 weighted member causes a longitudinal movement of the sleeve, an insulating member on the sleeve, a contact ring carried by said insulating member, and fixed contact segments adapted to be engaged by said 20 ring when the parts are in starting position.

8. In a starting switch of the character specified, the combination of a rotor, a sleeve 25 slidably mounted on the rotor shaft, segments arranged adjacent the rotor, a contact ring carried by and insulated from said sleeve adapted to engage said segments; arms connected with said sleeve, oppositely movable weight plates adapted to be movably connected to the rotor and adapted to be actuated by centrifugal force, said weights 30 having arms, engaging the arms on the sleeves, and springs connecting the weight members and acting in opposition to centrifugal force.

35 9. In a starting switch of the character specified, the combination of a rotor, contact segments arranged adjacent the rotor, a sleeve slidably mounted on the rotor shaft adjacent said contacts, a contact ring carried by and insulated from said sleeve adapted to engage said segments; arms connected with said sleeve and inclined at an angle of approximately 45° thereto, oppositely movable weight plates movably connected 40 to the rotor and adapted to be actuated by centrifugal force, said weight plates having arms inclined at an angle of 45° thereto and slidably engaging the arms on the sleeve, and springs connecting said weight-plates 45 and acting in opposition to centrifugal force.

50 10. For a centrifugal starting switch of the character specified, a radially movable weight member having an arm projecting therefrom at an angle of about 45° ; adapted 55 to engage an axially movable member whereby the radial movement of the weighted member causes a longitudinal movement of the axially movable member, substantially as described.

60 11. In a centrifugal starting switch of the character specified, a radially slidible weighted member, an axially movable sleeve having an arm projecting therefrom at an angle of about 45° , adapted 65 to be engaged by said weighted mem-

ber, whereby movement of the weighted member causes longitudinal movement of the sleeve, substantially as described.

12 In a centrifugal starting switch, a rotatable member, movable weights on said member adapted to be moved outwardly by centrifugal force, and having outwardly inclined angular portions, spring means for drawing the weights inwardly, an insulated contact carrier movable with the axis of 70 said member, and angular arms attached to the contact carrier engaging the outwardly inclined angular portions of the moving weights whereby the contact carrier is caused to move axially when the weights 75 move radially.

13. In a centrifugal starting switch slideable radially movable weights adapted to be attached to a rotatable part, and having 80 outwardly inclined angular portions, a 85 member movable axially of said part, and inclined portions on said axially movable member engaging the inclined portions on said weights whereby when the weights slide outwardly the member is moved proportionally inwardly and vice versa; a rotatable contact carried on said axially movable member, and relatively fixed contact members adapted to be engaged by the rotatable 90 contact when the parts are in normal position.

14. In a centrifugal starting switch, a pair 95 of contact members, an annular contact member adapted to contact therewith, an insulating support for annular contact member, an axially movable member carrying said annular contact member, an inclined arm attached to said axially movable member, a radially movable weight adapted to be 100 attached to a rotor and an arm on said weight inclined oppositely to and having a 105 slideable engagement with the arm on said axially movable member, whereby when the weight is moved radially outward the axially movable member is caused to move to 110 separate the contacts and vice versa.

15. In a centrifugal starting switch of the character specified, a radially movable weight member having an arm projecting angularly therefrom; and an axially movable member having an arm projecting angularly therefrom and opposite to the arm on the weight member said arms being inter-engaged, whereby the radial movement 115 of the weight member causes a movement of the axially movable member.

16. In a centrifugal starting switch a rotatable member, weights on said member adapted to be moved outwardly by centrifugal force and having inwardly inclined arms, an electrical contact having arms inclined oppositely to and engaging the arms on the weights for moving said electrical contact member in a plane at right angles 120 to the rotatable member, into or out of con- 125

tacting position, and springs adjustably connected with said weights, substantially as described.

17. In a centrifugal starting switch a rotatable member, movable weights on said member adapted to be moved outwardly by centrifugal force and having inwardly inclined arms, fixed electrical contacts, a movable electrical contact having arms inclined oppositely to and engaging the arms on the

weights for moving the inclined contact member to or from the fixed contacts, said weights being provided with a plurality of holes and springs having their ends adjustably engaged with the holes in the weights, substantially as described. 15

In testimony that we claim the foregoing as our own, we affix our signatures.

MARK A. DEFIBAUGH.

RALPH J. THIEMAN
